Inventor
Henry Mac Null Parson.

UNITED STATES PATENT OFFICE.

HENRY MACNUTT PARSON, OF NEW YORK, N. Y., ASSIGNOR TO PARSON MANUFACTURING COMPANY, OF NEW YORK, N. Y., A CORPORATION OF NEW YORK.

MECHANICAL STOKER.

1,027,753.

Specification of Letters Patent. Patented May 28, 1912.

Application filed November 22, 1906. Serial No. 344,606.

To all whom it may concern:

Be it known that I, HENRY MACNUTT PARSON, citizen of the United States of America, and resident of the city, county, 5 and State of New York, have invented certain new and useful Improvements in Mechanical Stokers, of which the following is a specification.

My invention relates to a mechanical 10 stoker, the structure of which is simpler, more durable, and better protected from the effects of heat, and the operation of which is more efficient and less complicated in action than that of the mechanical stokers 15 heretofore in use.

Various features of my device, which are 20 herein shown and described but not claimed, are shown, described and claimed in my co-pending application, Serial No. 344,605, filed November 22nd, 1906.

The construction of my stoker is such 25 that the fuel is fed with regularity to the grate in the form of particles of coke of substantially uniform size.

Difficulty has been experienced in breaking fuel which has been coked within the 30 furnace, into particles of substantially uniform size, and in feeding the same with regularity to all points of the upper end of 35 the grate. Those coke breakers heretofore in use have been unreliable or unsatisfactory in that they have either not properly broken the coke, or have impeded the flow of the same to the grate, and furthermore 40 have been complicated in operation.

I have invented a novel means for breaking and feeding the fuel to the grate, consisting preferably of a reciprocating bar, 45 which acts, first, as a part of the coking 50 surface, to allow the fuel to coke in a sheet over it, and then, by receding and advancing, to withdraw its support from the sheet of coke, crack the sheet on a line parallel to the grate, and feed the same in a 55 crumpled mass evenly to all points of the 60 top of the grate.

Having set forth the objects and nature 65 of my invention, I will now describe an embodiment of the same in connection with 70 the accompanying drawings in which—

Figure I is a view in cross-sectional elevation of my assembled stoker, Fig. II is 75 a plan view of the same, partly broken away to show the grate bar supports. Fig.

III is a view in cross-sectional elevation of 55 my assembled coke breaking device. Fig. IV is a top plan detail view of the coke breaker plate. Fig. V is a cross-sectional view on the line 5—5 of Fig. IV.

Referring to the drawings, in Fig. I the 60 front wall of the furnace is indicated by 1. Located in front of the wall 1, is the coal 65 hopper 2, communicating with the interior of the furnace through the opening 3. Below the mouth of the hopper is a guide 70 plate 4 for directing the fuel toward the opening 3, and operating below and in front of the guide plate 4, and in guideways 5, is a fuel feeder or pusher 6. This feeder reciprocates in its guideways and is operated 75 from the power shaft 7 by means of crank arms 8, connecting rods 9, bell crank levers 10 on shaft 11 and rods 12 pivotally connected to the feeder or pusher 6. As is common in the art, provision is made for 80 varying the stroke of the pusher 6 by means of a sleeve 13, mounted loosely on the rod 9 and attached to the arm 14 of the bell crank lever 10. The lost motion thus provided for between the rod 9 and the bell 85 crank lever 10, is adjusted at will by means of a nut 15, threaded to engage the rod 9 and to be locked at any desired position thereon by a lock nut 16.

Immediately within the opening 3 of the 90 furnace, is a plate 17 supported on the stoker frame sidepiece 19, which together with the plate 20 of the coke breaker (see Fig. IV) forms a coking surface for the fuel fed through the opening 3 before such 95 fuel is fed to the grate below. The plate 20 of the coke breaker when in its normal position forms, as just mentioned, in effect a section of the coking surface. This plate rests loosely upon bar 21' and engages the 100 forward face of the latter by means of its webs 22, and the rear face thereof by means of a flange 23. The bar 21', is mounted to slide upon guideways 24 on the frame side piece 19, and on the rear face of the upper 105 stationary grate section 21. When in its normal position the plate 20 lies partially under the plate 17 and rests at its forward end on the top of the grate section 21. By sliding the bar 21' outward so that the rear end of the plate 20 lies beyond the forward end of the plate 17, the plate 20 may be lifted off the bar 21'. This ready means of de-

taching the plate 20 from the bar 21' is very useful, as in the event of injury by heat or otherwise to the plate 20, it may be easily replaced. In order that, if in case the plate 5 20 be but slightly injured, it need not be entirely lost, it is preferably made in sections of less length than the bar 21'; and only the sections injured need be replaced. The upper surface of the plate 20, it will be 10 noted, is so shaped as to present a pair of longitudinal ridges 25 and 26. The function of these ridges is to impede the passage of the fuel over the coking surface, and to hold the fuel on the coking surface until it is 15 coked and ejected therefrom by the breaker. That the ridges or projections 25 and 26 may not be injured by heat, a series of twyvers or air holes 27 (see Fig. V) is provided between the projections 25 and 26, and on 20 either side of projection 25.

The breaker bar 21' reciprocates in its guide ways, carrying with it the plate 20, by virtue of the connecting rods 28 threaded through the uprights 29 of the bar 21', and 25 passing through openings 30 in the front plate of the furnace into outwardly extending elongated bearings 31 with which they have sliding engagement by virtue of packing 32. The rods 28 receive movement from 30 the power shaft 7 by means of cranks 33 and connecting rods 34, adjustably connected with the rods 28 whereby the throw of the latter may be varied.

In operation the fuel drops from the hopper 2 into the path of the pusher 6, by which 35 it is forced through the opening 3 of the furnace and falls across the coking surface. At this moment the coke breaker is in the position indicated in Fig. I and the projected ridges thereon serve to arrest the passage of the fuel across it. In this position 40 the fuel is subjected to the intense heat of the furnace without sufficient draft and is coked. The movement of the coke breaker shaft now causes the coke breaker to recede and withdraw its support from the fuel coking 45 above it, whereupon the sheet of coke cracks longitudinally on the line of the coke breaker and partially collapses into the recess left as the coke breaker recedes: the coke breaker then advancing engages the broken sheet of coke and turns or forces the 50

same over on to the grate in a thoroughly broken condition.

Although I have described in detail the 55 structure which now appears to me as the preferable embodiment of my invention, yet it is obvious that the particular structure shown is capable of considerable variation within the scope of the invention.

Having thus described my invention what I claim and desire to secure by Letters Patent is:—

1. In a mechanical stoker, a coking plate having a coking surface, a reciprocating coke breaking bar or plate beneath the coking plate normally substantially flush with the coking surface, the face of the reciprocating bar having a series of projections thereon to impede the passage of the fuel across the 70 same.

2. In a mechanical stoker, a coking plate having a coking surface, a reciprocating coke breaking bar or plate beneath the coking plate normally substantially flush with the 75 coking surface, the face of the reciprocating bar having a series of projections thereon to impede the passage of the fuel across the same, and air holes between said projections for cooling the same.

3. In a mechanical stoker, a coking plate having a coking surface, a coke-breaker co-acting therewith, the coke-breaker comprising a reciprocating bar and a movable transverse supporting bar with which the reciprocating bar is removably interlocked, the transverse supporting bar having its surface 80 normally substantially flush with the coking surface.

4. In a mechanical stoker, a coking plate, 90 a coke-breaker co-acting therewith, the coke-breaker comprising a bar and a movable support with which the bar is loosely interlocked, the plate having on its coke-engaging surface a series of longitudinal ridges with 95 air holes between the same for keeping them cool.

Signed by me at New York city, N. Y., this 19th day of November, 1906.

HENRY MACNUTT PARSON.
